RADIO RANGE

David G. C. Luck, Merchantville, N. J., assignor
to Radio Corporation of America, a corporation
of Delaware

Application March 31, 1942, Serial No. 436,933

6 Claims. (Cl. 250—11)

This invention relates to radio ranges, and more particularly to course and quadrant identifications in a four-course simultaneous range. In U. S. Patent No. 2,314,795 granted to D. G. C. Luck on March 23, 1943, and entitled Radio ranges, systems of quadrant identification for four-course ranges by means of phase reference modulation were described. Application Serial No. 436,430, filed by D. G. C. Luck on March 27, 1942, and entitled Radio ranges, describes a reference phase generator providing a tone definitely related in phase to the course tone but at an odd integral harmonic or subharmonic frequency.

An object of the present invention is the provision of means for identifying the courses and quadrants of a radio range in which a special reference tone is non-directionally radiated. Another object of the invention is the provision of a device for connection to the output of a mobile range receiver which will give a direct visual quadrant identification. A further object is the provision of a method of identifying the courses and quadrants of a four course radio range.

The invention will be described with reference to the accompanying drawing, of which Fig. 1 is a graph of a radio range pattern; Fig. 2 is a schematic block diagram of the device of the invention; and Fig. 3 is a schematic block diagram of a modification of the invention.

Referring to Fig. 1, the equisignal courses I, II, III and IV are indicated at the lines along which a receiver will pick up signals A and N with equal intensity from the range transmitters. The directive radiation patterns of the range antennas are illustrated as overlapping figures-of-eight with lobes of opposite polarities, arbitrarily designated as positive and negative. In the usual four-course simultaneous range, a non-directional antenna is used to radiate a carrier, which may be modulated with speech, or in the present instance, with a reference tone. The sidebands, modulated at 1020 cycles per second, the so-called course tone, are directionally radiated by the range antennas and keyed by interlocking A (—) and N (—) signals respectively as indicated in Fig. 1. As described in the aforementioned patent, the non-directional carrier may be modulated with a reference tone related in phase and frequency to the course tone for providing an indication to the operator of a receiving station of the course or quadrant in which the receiving station is located.

With a range set up for a reference tone of 55

one-third the frequency of the course tone, the transmitter phases may be adjusted so that a course tone peak occurs simultaneously with a reference tone peak in the pattern lobes marked plus (+), while a course tone trough coincides with the reference tone peak in the lobes marked minus (—) in Fig. 1. The function of the device of the invention is then to actuate an indicator in accordance with the phase relationship between the course and reference tones to show the course or quadrant in which the receiver lies.

Referring to Fig. 2, the output terminals of a range receiver are connected through a filter 7, adjusted to pass the course tone which in the usual installation is 1020 cycles per second, to a limiter 33, thence through a second course tone filter 35 to the primaries 37 and 41 of a pair of transformers 51 and 53. The range receiver output is also connected through an adjustable phase shifter 25 and a filter 27 adjusted to pass the reference tone which in this case is one third the frequency of the course tone, or 340 cycles per second, to a limiter 29, thence through a 1020 cycle pass filter 31 to the primaries 39 and 43 of the transformers 51 and 53. Voltage responsive indicator devices, such as neon lamps 45 and 47, are connected across the secondaries of the transformers 51 and 53, respectively.

The operation of the device is as follows: The 30 1020 cycle course tone is separated from the receiver output by the filter 7, and limited to a constant peak amplitude by the limiter 33. Since the limiting operation clips off the peaks of the waves, the limiter output is non-sinusoidal, but 35 contains harmonics of the original 1020 cycle wave. The harmonics are removed by the 1020 cycle filter 35, resulting in a substantially constant amplitude 1020 cycle sine wave, related in phase, or more properly speaking, in polarity, 40 to the predetermined polarity of the range quadrant in which the apparatus is located.

The 340 cycle reference phase voltage is separated from the receiver output by the filter 27, and limited to a constant amplitude by the limiter 45 29. The non-sinusoidal output of the limiter 29 contains a third, or 1020 cycle harmonic of the 340 cycle reference wave. This harmonic component is separated from the limiter output by the filter 31. This third harmonic voltage remains in constant phase, since it is derived from the 340 cycle reference phase modulation of the non-directional range transmitter. The phase control 25 is merely used as an initial adjustment for compensating phase shifts inherent in the range receiver and filters, and once adjusted

requires no further attention as long as the same receiver is used.

The constant phase constant amplitude third harmonic voltage from the filter 31 is applied to the primaries 39 and 43 of the transformers 51 and 53, respectively, in opposite polarities as indicated in Fig. 2; the constant amplitude voltage from the filter 35 is applied to the primaries 37 and 41 of the transformers 51 and 53 in the same polarity. Thus when the two 1020 cycle voltages derived from the course tone and reference tone are in phase, their effects will add in one of the transformers and subtract in the other; when they are 180° out of phase, they will subtract in the first transformer and add in the second. These conditions correspond to positions of the range receiver in positive and negative quadrants, respectively, of the range. Assuming the connections to be such that the in-phase voltages will add in the transformer 51 and subtract in the transformer 53, the neon lamp 45 will flash when the two 1020 cycle voltages are in phase, corresponding to a location of the receiver in one of the positive quadrants illustrated in Fig. 1. Similarly, the lamp 47 will flash when the receiver is in one of the negative quadrants. The A and N keying of the course tone will cause the visual indications to flash accordingly, so that if the receiver is in a positive "A" lobe the lamp 45 will flash A (—); in a negative A lobe the lamp 47 will flash A, and so on. When the receiver is lying in one of the course lines, the operation of each lamp is similarly related to the polarity and keying of the two overlapping lobes defining the course line. Thus, along the course marked I, the lamp 45 will be actuated by both the A and N keying, and so will give a steady indication, while the lamp 47 gives none. Along course II, the positive lamp 45 flashes A, while the negative lamp 47 flashes N.

Referring to Fig. 3, the output terminals of the range receiver are connected to the primary of a transformer 1, provided with two secondary windings 3 and 5. The secondary 3 is connected through a filter 7 to the input of an amplifier 9, which is preferably designed to act as a limiter. The filter 7 is adjusted to pass the 1020 cycle course tone. The amplifier 9 terminates in a push-pull circuit which includes the primary windings of a pair of transformers 11 and 13. The secondaries of the transformers 11 and 13 are connected to a pair of rectifiers 15 and 17 which are connected to supply control voltages to the ray control electrodes of an electron ray indicator tube 23, which may be a twin indicator tube such as the RCA 6AF6G. The secondary 5 of the transformer 1 is connected through an adjustable phase shifting network 25 and a filter 27 to a limiter 29. The filter 27 is designed to pass the 340 cycle reference tone. The limiter 29 clips off the peaks of the 340 cycle voltage, producing a substantially square wave form containing strong odd harmonics of the 340-cycle input. The third harmonic, at 1020 cycles per second, is selected by a filter 31. The third harmonic voltage, which is of constant phase as explained previously, from the filter 31 is applied in series with the plate voltage supply to the push-pull output tubes of the amplifier 9, through the primaries of the transformers 11 and 13.

The 1020-cycle course tone is added to and subtracted from the 1020-cycle constant phase third harmonic of the reference tone. The resultant outputs at the transformers 11 and 13 are then

uniquely related to the relative polarities of the two 1020 cycle voltages and hence to the quadrant in which the range receiver is located. For example, suppose that the circuit is so arranged that output of the amplifier 9 to the transformer 11 is in phase with the input to the amplifier. Then since the amplifier provides a push-pull output, the voltage produced by the amplifier across the primary of the transformer 13 is 180 degrees out of phase with the input. Now if the 1020-cycle third harmonic voltage is in phase with the course tone input to the amplifier 9, it will add to the amplifier output in the transformer 11 and subtract from the amplifier output in the transformer 13. Thus the voltage applied to the rectifier 15 will be greater than that applied to the rectifier 17, which latter may in fact be zero if the apparatus is adjusted so that the two 1020 cycle voltages are of equal amplitudes in the primaries of the transformers 11 and 13. The limiting characteristic of the amplifier 9 mentioned above makes it unnecessary to adjust the amplitudes of the two 1020 cycle voltages for different amplitudes of receiver output. The control electrode 19 of the indicator 23 will then be energized causing a visual indication to be displayed by the corresponding section of the target 24 in the well known manner, while the electrode 21 will not operate. Similarly, the lower section of the target will be caused to indicate when the two 1020-cycle voltages are out of phase, corresponding to a location of the receiver in one of the negative quadrants illustrated in Fig. 1. The indications of the upper and lower sections of the tube 23 correspond to the courses and quadrants of the range in the same manner as the flashes of the indicators 45 and 47 of Fig. 2.

The illustrated devices may be modified in many ways without departing from the spirit of the invention; for example, the filter 35 of Fig. 2 may be omitted, resulting in less complete cancellation of the bucking 1020 cycle waves, but not seriously affecting the operation of the device 45 when neon tube indicators are used, since such indicators will not flash until a comparatively high voltage is applied. The amplifier 9 of Fig. 3 might be replaced by a balanced modulator, and the rectifiers 15 and 17 omitted, without changing the operation, since the balanced modulator would be self-rectifying.

Thus the invention has been described as a device which utilizes the usual directionally radiated course tone modulation of a simultaneous four course radio range, together with a special non-directionally radiated harmonically related reference tone, to give a visual course and quadrant identification. This is accomplished by comparing the phase or polarity of the course tone with that of the constant phase reference tone and actuating an indicator accordingly.

I claim as my invention:

1. A visual course and quadrant identification device for a four course simultaneous radio range including in combination a radio receiver, filters for separating two harmonically related modulation components in the output of said receiver, harmonic generating means for deriving from the lower frequency one of said components a harmonic having a frequency equal to that of the higher frequency one of said components, means for combining said harmonic with said higher frequency additively in one circuit and subtractively in another circuit, and two visual indicators connected to said first and sec-

ond circuits respectively to respond to said resultant voltages.

2. A device for indicating the phase of an alternating voltage with respect to a reference voltage alternating at a frequency harmonically related to that of said first voltage, including in combination a harmonic generator controlled by the lower frequency one of said voltages to produce a harmonic bearing a fixed phase relation to said lower frequency voltage and having a frequency equal to that of the higher frequency one of said first-named voltages, means for combining said harmonic voltage with said higher frequency voltage additively in one circuit and subtractively in another circuit, and two voltage amplitude responsive indicating means connected to said first and second circuits respectively to respond to the resultant combined voltage in each of said circuits.

3. A device for providing an indication of the phase relation between two harmonically related components of a complex wave, including in combination filter means arranged to separate said components, wave shape modification means for producing from the lower frequency one of said components a non-sinusoidal wave having a harmonic component of a frequency equal to that of the higher frequency one of said first named components and having a fixed phase relationship to the lower frequency one of said first named components, filter means for separating said harmonic from said non-sinusoidal wave, and two amplitude responsive indicating devices connected to be controlled by the sum and the difference respectively of said higher frequency one of said first-named components and said last-named harmonic component.

4. The method of identifying the courses and quadrants of a four course simultaneous radio range which directionally radiates keyed course tone modulated signals and non-directionally radiates a constant phase reference tone modulated signal, comprising the steps of deriving the modulations from said signals, separating the

course tone component from the reference tone component, limiting each of said separated components to a constant voltage amplitude, deriving from the lower frequency one of said components a harmonic voltage having a frequency equal to that of the higher frequency one of said components, adding said harmonic voltage to said higher frequency component voltage and producing an indication related to the sum of said voltages, and subtracting said harmonic voltage from said higher frequency voltage and producing a second indication related to the difference of said voltages.

5. The method of indicating the phase of an alternating voltage with respect to a reference voltage alternating at a frequency harmonically related to that of said first voltage, comprising the steps of deriving from the lower frequency one of said voltages a harmonic bearing a fixed phase relation to said lower frequency voltage and having a frequency equal to that of the higher frequency one of said first-named voltages, producing one indication in accordance with the sum of said harmonic voltage and said higher frequency voltage, and producing a second indication in accordance with the difference of said harmonic voltage and said higher frequency voltage.

6. The method of determining the phase relation between two harmonically related components of a complex wave, comprising the steps of separating said components, modifying the wave shape of the lower frequency one of said components to derive a non-sinusoidal wave having a harmonic component of a frequency equal to that of the higher frequency one of said first named components, separating said harmonic from said non-sinusoidal wave, and producing indications in accordance with the sum and the difference respectively of said higher frequency one of said first named components and said last named harmonic component.
